UNITED STATES PATENT OFFICE.

CHARLES F. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

ELECTRIC SWITCH AND STOP FOR WINDING DRUMS.

1,422,181.

Specification of Letters Patent.

Patented July 11, 1922.

Application filed March 21, 1922. Serial No. 545,445.

To all whom it may concern:

Be it known that I, CHARLES F. CUNO, a citizen of the United States of America, residing at Meriden, Connecticut, have invented a new and useful Electric Switch and Stop for Winding Drums, of which the following is a specification.

My invention relates to improvements in winding devices for trouble lamps, cigar 10 lighters and other translating devices which are carried by a cord designed to be wound and unwound upon a spool or drum and particularly to a means which will hold the drum against rewinding when the cord is extended 15 and the circuit is "on." The present invention is primarily an improvement upon the structure set forth in Charles H. Cuno's application, Serial No. 533,828, filed February 3rd, 1922, and it will be necessary herein to 20 describe in detail only such features as constitute the improvement hereinafter claimed.

In the accompanying drawing:

Fig. 1 is a side view of a device embodying the improvements of my invention, the 25 parts being shown in the open circuit or "off" position.

Fig. 2 is a front elevation, the parts being shown in the closed circuit or "on" position.

Fig. 3 is a perspective view of the reel and combined latch and circuit closer, as shown in Fig. 2.

In describing the present invention I will employ the same characters as used in the 35 aforesaid application to designate corresponding parts herein.

5 represents a suitable casing having the face plate 6 with the outlet 7 for the cable indicated at C. 8 represents the hub of a rotatable drum or reel arranged within the housing and rotatable upon shaft 9. The flange 10 of the drum contains the usual rewinding spring well known in devices of this kind and which serves to rewind the drum 40 for the purpose of winding up the cable thereon. 11 is a binding post mounted on the casing. 12 is the other flange of the drum insulated from the flange 10 by the hub 8. The cable C comprises two wires 50 one being connected to the flange 10 which is electrically connected with the binding post 11 by being grounded on the case, the other being connected to the flange 12. Alongside the flange 12 I mount a contact 55 arm 13 which is electrically connected with

an insulated binding post 15. This arm is preferably in the form of a spring which normally moves away from the flange 12 unless held in contact therewith. Through the medium of this arm 13 the circuit 60 through the cable is opened and closed, that is to say, when the arm 13 bears against the flange 12, as shown in Fig. 2, the circuit is closed or "on," and when it is disengaged therefrom the circuit is "off" or open. In 65 the particular form shown, I provide means for disengaging the arm 13 from the flange 12 which comprises a slide 20 mounted in suitable guides to be moved to and fro by a suitable handle or button 26. 16 is a strip of 70 insulation which overstands the outside of the contact arm 13. Between the insulation and the arm 20 I provide a spacer preferably in the form of a ball 18. 21 is a depression in one part of the arm 20. The ball as shown 75 in the former application referred to, is supported so that it may move only toward and from the flange 12. When the arm 20 is pushed in as shown in Fig. 1, the depression 21 stands over the ball allowing the latter to 80 recede sufficiently so that the arm 13 will not bear against the flange 12 (see Fig. 1). When, however, the button or handle 16 is pulled out the arm 20 pushes the ball or spacer piece 18 forwardly and forces the 85 contact 13 into engagement with the flange 12 to close the circuit, as shown in Fig. 2. Thus far the parts described correspond with the similar parts described in the aforesaid application. My improvement 90 comprises providing means which will operate to hold the reel against rewinding when the circuit is closed thereby making it easy for the user to hold the lamp or other translating device (not shown) in its extended position. In the particular form shown, I have 95 shown a hook 13^a at the end of the arm 13 and I have provided the equivalent of ratchet teeth on the flange 12. In the particular form shown, these ratchet teeth are 100 formed by striking in a portion of the metal of the flange on a bevel as indicated at 12^a—12^b leaving one abrupt edge for engagement by the hook 13^a. In the drawings, it will be observed that I have shown four of 105 such recesses. The number however is immaterial.

In operation: Assuming the handle 26 is pulled out to close the circuit the hooked end 13^a of the arm 13 will bear against the 110

side of the flange 12. As the cable is pulled out the reel may freely turn in the direction of the arrow, the hooked end of the contact member riding up the several inclines of the 5 ratchet teeth as the arm yields. If the cable is released it is obvious that the hooked end 13^a of the arm will engage the abrupt wall of one or another of the said recesses and thereby hold the reel against rewinding 10 until the hooked end 13^a of the arm is disengaged from the flange 12. Just as soon as the operator presses the button in to move it to the open circuit position, the latch as I may term the hooked end 13^a, leaves the 15 reel free to rewind the cable thereon. By this very simple expedient I obtain at a minimum of expense a reliable and serviceable reel lock for the reel or drum.

It should be understood of course that I 20 have shown the invention in a very crude and simple form and that I anticipate that many changes may be made therein without departure from the spirit and scope of the invention as claimed.

25 What I claim is:

1. In a device of the character described, a self-rewinding drum, a cable carried thereby and in circuit therewith, a circuit closer, means for manually operating the same and

means cooperating with said circuit closer to 30 lock the drum against rewinding when the circuit closer is in the closed circuit position and leaving said drum free to rewind when the same is in the open circuit position.

2. In a device of the character described, 35 a self-winding reel, a cable for carrying a translating device mounted on said drum to unwind the same as the cable is extended, a combined circuit closer and latch with means for manually operating the same to close the 40 circuit through said cable and to engage said drum to hold the same against rewinding while the circuit is "on".

3. In a device of the character described, 45 a self-winding reel, a cable for carrying a translating device mounted on said drum to unwind the same as the cable is extended, a combined circuit closer and latch with means for manually operating the same to close the 50 circuit through said cable and to engage said drum to hold the same against rewinding while the circuit is "on", said circuit closer comprising means arranged to bear against the side of said drum, with ratchets on the drum and a latch associated 55 with said means for coacting with said ratchets.

CHARLES F. CUNO.
